UNITED STATES PATENT OFFICE.

EMILE F. LOISEAU, OF MAUCH CHUNK, PENNSYLVANIA.

IMPROVEMENT IN MACHINES FOR WATER-PROOFING ARTIFICIAL FUEL.

Specification forming part of Letters Patent No. 147,666, dated February 17, 1874; application filed September 20, 1873.

To all whom it may concern:

Be it known that I, EMILE F. LOISEAU, of Mauch Chunk, in the county of Carbon and State of Pennsylvania, have invented a new and useful Improvement in Machine for Water-Proofing Artificial Fuel, of which the following is a specification:

In the manufacture of artificial fuel from coal-dust, or from a combination of coal-dust and other substances, it is extremely desirable to render the lumps or blocks water-proof, so that the fuel will not be injured by exposure to the weather; and not only that, but it is also desirable to give the lumps a coating which will render them less liable to disintegrate or be broken; and my object in this invention is to provide a suitable apparatus for water-proofing or coating the lumps of artificial fuel; and it consists in a machine having an endless belt or apron and tank, with the apron constructed and made to dip into the tank and immerse the fuel thereon, substantially in the manner hereinafter described.

In the accompanying drawing, Figure 1 represents a top or plan view of the machine. Fig. 2 is a vertical longitudinal section of Fig. 1, taken on the line *x x*. Fig. 3 is a cross-section of the tank, taken on the line *y y*.

Similar letters of reference indicate corresponding parts.

A is the bed-plate. *B* represents stands on each end of the bed-plate, which support the drums of the endless belt or apron. *C* are the drums, and *D* is the apron. *E* represents the tank, which is supported by stands *F F* between the apron-drums. *G* is a drip-pan, which receives any excess of the water-proofing liquid, and conducts it to the central opening *H*, which discharges it into a proper reservoir. Each edge of the apron *D* is strengthened by a rope, and is provided with a series of balls, *I*. *J* represents recesses in the sur-

face of the drums *C*, which, as the apron revolves, the balls enter, and serve as cogs to propel and keep the belt from slipping on the drums. The motive power is applied by means of a crank, *K*, or pulley on the end of one of the drum-shafts. The tank *E* is supplied with the coating-liquid from an elevated reservoir, or the liquid is pumped up from below. The apron is made to dip into the liquid and submerge the lumps of artificial fuel which it carries by means of the grooves *L L* of the inner sides of the tank, in which grooves the balls *I* travel as the belt revolves. *M* are buckets, which extend across the apron to prevent the rolling or movement of the lumps of fuel when passing in or out of the tank. The lumps of artificial fuel are delivered onto the apron and carried through the liquid, and thereby receive a thorough coating. This coating immediately dries and becomes hard upon exposure to the air, and forms a perfect water-proof covering. The apron takes the coated fuel from the tank, and delivers it into a cart or other receptacle ready for use.

Having thus described my invention, I claim as new and desire to secure by Letters Patent—

1. A machine for coating or water-proofing artificial fuel, having a revolving apron, which is made to dip into a tank by means of balls and grooves, substantially as and for the purposes described.
2. In combination with a machine for coating artificial fuel, the drip-pan *G*, constructed and arranged as shown and described.
3. In combination with the apron *D*, the balls *I* and buckets *M*, as and for the purposes herein shown and described.

EMILE F. LOISEAU.
